DESIGN FOR A LIGHTING FIXTURE

George E. Glatthar, University Heights, and
Frederick Wening, South Euclid, Ohio

Application April 28, 1934, Serial No. 51,582

Term of patent 3½ years

To all whom it may concern:

Be it known that we, GEORGE E. GLATTHAR and FREDERICK WENING, citizens of the United States, and respectively residing at University Heights, and South Euclid, in the county of Cuyahoga and State of Ohio, have invented a new, original, and ornamental Design for Lighting Fixtures, of which the following is a specification, reference being had to the accompanying drawing forming a part thereof.

In said drawing, Fig. 1 is a side elevation of a

lighting fixture showing our new design as suspended from a ceiling or the like; Fig. 2 is an end elevation thereof, looking upwardly as viewed in Fig. 1 and downwardly as viewed in Fig. 3; and Fig. 3 is a side elevation of said fixture as used in a table lamp or the like.

We claim:

The ornamental design for a lighting fixture, as shown.

GEORGE E. GLATTHAR.
FREDERICK WENING.
